(No Model.)

G. F. RAPP.
SHOE.

No. 436,544.

Patented Sept. 16, 1890.

UNITED STATES PATENT OFFICE.

GEORGE F. RAPP, OF ST. LOUIS, MISSOURI.

SHOE.

SPECIFICATION forming part of Letters Patent No. 436,544, dated September 16, 1890.

Application filed April 5, 1890. Serial No. 346,711. (No model.)

To all whom it may concern:

Be it known that I, GEORGE F. RAPP, of St. Louis, in the State of Missouri, have invented certain new and useful Improvements 5 in Elastic Tongues for Lace-Shoes, of which the following is a full, clear, and exact description, reference being had to the accompanying drawings, forming a part hereof.

My invention appertains to an improvement 10 in elastic shoe-tongues for lace-shoes; and it consists in certain novel features in the construction thereof, as will be herein-after more fully set forth.

In the drawings, Figure 1 is an under side 15 view of my improved tongue as applied to the upper of a lace-shoe. Fig. 2 is a perspective view of my invention as applied to the shoe. Fig. 3 is a cross-section taken on line $x-x$ of Fig. 1, and Fig. 4 is a front elevation of the 20 tongue partly broken away.

Referring to the drawings, 1 represents the shoe-upper of an ordinary lace-shoe to, which my tongue can be readily attached.

2 is the tongue having an elongated opening 25 over which the elastic gore is sewed.

5 5 represent two lips formed by cutting the tongue a short distance horizontally from the edges of the elongated opening 3, as shown. The elastic gore is placed between 30 the under surface of said lips 5 5 and the face of the tongue, the said gore being stitched to the tongue in this position. By this means the elastic gore is securely fastened to the tongue, and at the same time presents a neat 35 and attractive appearance. The tongue is stitched to both edges of the upper at its lower end and extends upwardly for about one-half its length, the stitches terminating

at about this point and being run laterally in V-shaped design, as indicated at 6, to prevent ripping, &c. By thus attaching the tongue to the upper, as shown, the same is always held in position, and, furthermore, all dirt and water will be effectually excluded from the shoe.

It is further to be noted that the shoe may be unlaced at any time, but will still hug the foot of the wearer just closely enough to make a good appearance, feeling as easy as a slipper, yet not being too loose on the foot.

I am aware that prior to my invention various parts of a shoe have been provided with elastic gores to act as a protection for the foot, also that elastic flaps have been used in connection with button-shoes; but

What I claim, and desire to secure by Letters Patent, is—

As an improved article of manufacture, the hereinbefore-described lace-shoe having a tongue fastened or secured to both edges of the upper at a sufficient distance from the edge thereof to permit lacing, the said tongue having an elongated opening therein, lips at one end of the said opening formed by cutting the tongue, and an elastic gore, having 60 projections upon its sides, sewed upon the lower surface of the said tongue and above the said lips, the said elastic gore covering the elongated opening, as and for the purpose described.

In testimony whereof I affix my signature in presence of two witnesses.

GEORGE F. RAPP.

Witnesses:

C. F. KEELER,
JNO. C. HIGDON.
